FIG. 2.

BY
Charles P. Griffin
ATTORNEY.

UNITED STATES PATENT OFFICE.

MARSHALL H. PAGE, OF SAN FRANCISCO, CALIFORNIA, ASSIGNOR, BY MESNE ASSIGNMENTS, TO WILLIAM A. GARLICK.

CARD-DISPLAY-ADVERTISING MACHINE.

Application filed March 7, 1927. Serial No. 173,424.

This invention relates to a card display advertising machine of a type in which the cards are picked up one at a time, lifted out of a receptacle containing a number of such cards, displayed for a few seconds, or as long as may be desired, returned to the receptacle and again picked up in succession, the cards in the present instance being picked up from the front of a pile of cards and after being displayed for a short time being then restored to the card receptacle at the back of the entire set of cards.

Means are also provided to hold the cards in place on the card support positively during a portion of the card movement to prevent them from being dropped during another portion of the movement of the arms for displaying the cards. The arms push them back into the card receptacle without regard to the lifting device which thereafter engages the front card of the series to present it to the public upon the next upward movement of the arms.

An object of the invention is to provide a type of reduction gear drive which can be arranged in a very small compass, and which will make no other reduction gear necessary, the present reduction gear being entirely enclosed within an oil proof case.

Another object of the invention is to reduce the operating mechanism to the smallest possible compass in order to make it possible to produce the machines as cheaply as possible, and at the same time to make it possible to run them upon the minimum of power, a small electric motor being used for the purpose of driving the machine.

Other objects of the invention will be apparent as the description proceeds.

An embodiment of the invention is shown in the accompanying drawings in which the same reference numeral is applied to the same portion throughout the several figures of the drawings and of which there may be modifications.

Figure 1 is a back view of the case and motor supporting stand, some of the parts being shown in cross section.

Figure 2 is a sectional end view of the cas-

ing for the machine showing the end of the 50 motor supporting stand and other operating parts, and

Figure 3 is a detail plan view showing the arrangement of the worm casing taken on line 3—3 of Figure 1.

The numerals 1, 2, 4 and 5 represent the bottom and sides of the receptacle containing the operating apparatus, 6 representing the top which has slots therethrough to permit the operation of the card lifting arms, and the 60 top also has an opening through which the cards are removed from, and restored to the card receptacle formed by the side 2 and partition 3.

The operating mechanism is mounted upon a small bench 7 which has four legs 8 to 11 inclusive, said bench having a small rectangular box 12 adjacent one end to act as the gear box for the two sets of reduction gears. This gear box has a flat cover 13 to retain 70 grease therein, and it has bearings for a shaft 14 with a coupling 15 to be connected with the motor couplings 16 on the motor shaft 17, which motor shaft projects from the motor casing 18, the motor being of just the proper 75 size to sit upon a small pad 19 at one end of the bench 7.

The shaft 14 has the worm gear 20 thereon, which worm gear is in mesh with a worm wheel 21. In actual practice it is convenient 80 to have the ratio between the worms and the worm wheel anywhere from 20 to 50 to 1. This makes it possible to retain a reduction of either about 400 to 1, or as high as 2,500 to 1 with only two reductions. The gear 21 is supported by a shaft 22 at right angles to the line of direction of the motor shaft, and it carries a worm 23 which is in turn in mesh with the worm wheel 24, this worm wheel being carried by the shaft 25 which is journaled in the sides 85 of the gear casing and projects therefrom to carry the cam 26 and commutator 27.

The cam 26 is something in the nature of a heart shaped gear in that its movement first causes the arms it lifts to rise to a given maximum, then to remain in that position for a considerable period of the movement of the cam, after which the arms are raised slightly

more by means of the portion 26', and are then returned to their lowest position to restore the cards to the card receptacle.

At one end of the supporting bench there 5 is a rectangular frame 28 which is secured to the main supporting frame by means of two bolts 29 and 30, and which has the anti-friction roller 31 at its forward upper corner. At the opposite end of the machine there is a sub- 10 stantially similar rectangular frame 28', said frames forming the support in which the shaft 31' is journaled. The shaft 31' carries the two arms 32 and 33, which arms are rigidly connected to said shaft and one of which 15 has a depending extra supporting arm 35 to form a proper support for the bearing roller 36 which roller bears upon the top of the cam 26 and forms the means for the continuous raising and lowering of the display cards.

20 The arms 32 extend over the top of the box, and they have depending hooks 38, one for each arm, which forms the means for engaging eyelets in the display cards and to lift them into the display position.

25 On the side of the arms there is a substantially L shaped plate 39, the depending arm of which is curved so that it will bear upon the roller 31 and hold it normally in the position in Figure 2, but during the time the 30 transfer of the lower edge of the card is being made from the front edge of the bundle to the back edge of the bundle it is very necessary to prevent the card from being dislodged from the hook 38, and this is accomplished by 35 allowing the depending curved arm of the member 39 to recede against the roller 31 at the curved portion 40. This allows the end of the member 39 indicated at 42 to come against the card and prevent it from being 40 unhooked momentarily, but as soon as the lower edge of the card has been brought back against the depending spring plate 43 which extends from the top of the casing in which the apparatus is assembled down into the card 45 receptacle between the side 2 and partition 3, the plate end 42 promptly releases the card and permits it to be removed from the hook while the arm at the same time operates with sufficient force to push the card down into 50 place against some little resistance.

The commutator 27 may have a separate commutator plate 27', and may be connected with two or four electrical connecting plates 47 to 50 inclusive, as may be required, said 55 contacts being carried by an insulated block 51 secured to the top of a small bracket 52 held in position by the nut on the bolt 30.

In operation, the cards are all kept in alignment by means of a thin piece of spring metal 60 53 at each end of the card compartment, and the cards are illuminated by means of a lamp 54 which is held in the desired place by the springs 55, 56, which also serve as the means for applying the electric current to the lamp.

A reflector 57 extends along the front of the 65 machine to prevent the lamps from interfering with a proper view of the cards by persons who may be looking at the advertising machines while they are working.

The operation of the machine is as follows: 70 Assuming a plurality of cards to be placed in the card receptacle, said cards being held back by means of the spring 46', and forward as much as they should be by means of the spring 46, the operation of the motor will cause the 75 worms to operate their corresponding worm wheels at a slow rate of speed to cause the heart shaped cam 26 to rotate slowly. This cam will bear upon the roller 36 and will successively raise the arms 32-33 and lower 80 them. As the arms 32-33 are raised the hook 38 on each arm will engage a corresponding hole in a card in the receptacle. The card will be lifted out and displayed for a few 85 seconds, after which it will be raised a little bit more to bring it over the top of the set of cards against the spring 46, whereupon the plate 39 will be placed against the edge of the card to hold it in place. The card will be held positively on the hook 38 only during the 90 time its front edge is transferring from the front pile of cards to the back of the pile of cards, whereupon the plate 39 will be disengaged from the cards and they will be free to be removed from the hook 38, but at the same 95 time the arms 32 and 33 push them down into the receptacle therefor, and when the arms do come down into a position to push the display card back into its place, the hooks 38 on each arm will at the same time pick up a new card 100 from the front of the pile. At the same time the cards are being displayed the lamp 54 is having current supplied thereto and discontinued therefrom to increase the attractive 105 appearance of the cards and machine and the operation of the machine is cyclic, a card being picked up, displayed, returned to the card receptacle, and a new card picked up continuously.

Having thus described my invention, what 110 I desire to secure by Letters Patent of the United States is as follows, but modifications may be made in carrying out the invention as shown in the drawings and in the above particularly described form thereof, within the 115 purview of the annexed claims.

I claim:

1. An advertising machine comprising a casing, a frame therein, a motor mounted on the frame, a reduction gear set to which the motor is directly coupled, a continuously rotating cam operated by the gear set, a card holding receptacle, a pair of arms having hooks to pick up the cards, and a roller on one of the arms bearing on said cam, the latter having its periphery so arranged as to cause the hooks on said arms to pick up a card, raise the arms to display the card in a 120 125 130

fixed position for a time, and then lower the arms and restore the card to the card receptacle.

2. An advertising machine comprising an enclosing casing having a card receptacle at its front portion, springs to hold cards in the desired position in said receptacle, a pair of arms each having a hook adapted to pick up a card by means of eyelets therein from the front of a series of cards placed in the card

receptacle, means on said arms for securely holding the card thereon during a portion of the card movement, and means to raise the card a little higher whereby the card is restored to the card receptacle at the back of 15 the series of cards following every display thereof.

In testimony whereof I have hereunto set my hand this 25th day of Feb., A. D. 1927.

MARSHALL H. PAGE.
